WILLIAM BEARD LAKE, OF BRAINTREE, ENGLAND.

LIFTING JACK.

Application filed September 7, 1926, Serial No. 134,061, and in Great Britain August 24, 1926.

This invention relates to improvements in lifting jacks.

The object of this invention is to provide a hydraulic jack which will have a high or double lift so that it will be suitable for use on vehicles fitted with balloon or over-sized tyres, the said jack being simple in construction and operable through the medium of a single valve.

10 A further object of this invention is to provide means for readily operating the valve when it is desired to raise or lower the jack, said jack being either of the garage type or of the ordinary type suitable for use on the 15 road.

With these and other objects in view, the invention consists in providing a hydraulic lifting jack which is adapted to be raised through the medium of a reciprocating pump 20 rod or like means and lowered by the rotation or partial rotation of the said pump rod or like means.

The invention further consists in providing in a hydraulic jack a single valve which 25 is adapted to control the raising and also the lowering of the jack.

The invention will now be described with reference to the accompanying drawings, in which:—

30 Figure 1 is a longitudinal sectional elevation of one form of jack constructed according to this invention and suitable for garage use;

Figure 2 is a sectional plan thereof;

35 Figure 3 is a cross section taken on the line $a-a$ of Figure 1;

Figure 4 is a cross section taken on the line $b-b$ of Figure 1;

40 Figure 5 is an enlarged sectional elevation of the upper portion of the jack casing showing the lower end of one of the plungers therein;

45 Figure 6 is an enlarged sectional elevation showing the co-operating means of the inner and outer plungers;

Figure 7 is an enlarged longitudinal sectional elevation of the valve and plunger, showing the plunger in use, the valve being in position for the lifting operation;

50 Figure 8 is a similar view to Figure 7 showing the valve operating means in use during the lowering operation;

55 Figure 9 is a sectional elevation of a modified form of hydraulic jack, suitable for ordinary use and for carrying on a car;

Figure 10 is a plan thereof;

Figure 11 is a cross section taken on the line $c-c$ of Figure 9;

Figure 12 is a perspective view of one end of the jack operating handle for use with the jack shown in Figures 9 and 10, and

Figure 13 is a perspective view of the outer end of the plunger rod.

Figure 14 is a sectional view, partly in elevation, showing the mounting of the connecting rod member and the connection therewith of the operating lever.

As shown, more particularly in Figures 1 to 8, a pair of telescopic plunger members 1 and 2 are mounted in a cylinder 3 formed in a casing 4 which contains an oil or like reservoir 5 from which oil is adapted to pass to the cylinder 3 by way of a valve 6. The casing 4 is provided with wheels 7 which are rotatably mounted and carried by a bracket 8 preferably formed integrally with the said casing 4.

To the sides of the casing 4 are pivotally mounted at 9 a pair of bracket-like supports 10 which are maintained in their adjusted position by springs or the like 11. In Figure 80 2 one bracket 10 is shown in its outwardly extended position and the other bracket 10 is shown folded back on the casing 4 so that the jack can be positioned adjacent to the wheel of the vehicle it is desired to lift. Within the 85 casing 4 is mounted a tubular member 12. This tubular member 12 is adapted to screw into a sleeve or the like 13 which carries the valve 6. This sleeve or the like 13 is mounted in a bore formed in an extension 14 of the wall 90 of the cylinder 3. The valve end of the sleeve 13 is positioned within an enlarged bore arranged adjacent to the lower end of the cylinder 3 and is threaded for the reception of a threaded closure member 15 which is formed 95 with apertures 16. This closure member 15 is adapted to form an adjustable abutment for a spring 17 which is adapted to act on the valve 6 and maintain it on its seating. A suitable 100 gauze screen is positioned in front of the apertures 16 of the member 15. The stem 18 of the valve 6 is preferably of triangular shape and is adapted to move in a circular bore to permit of the ingress and egress of oil. The valve 6 is preferably fitted or provided with a 105 washer. Radially arranged apertures 19 are also provided in the sleeve 13 for the passage of the oil. A portion of the enlarged bore of the sleeve 13 is screw-threaded at 20 for the reception of the threaded end 21 of a rod 22. The threaded end 21 is formed with a slot 23 to permit of the passage of the oil and a screen 110.

24 of gauze or other suitable material is positioned adjacent to the threaded extension 21 to prevent the entrance of dirt. The rod 22 is of square or other angular shape in cross section and is adapted to project within a similar shaped bore 25 formed in a plunger rod 26 which is adapted to reciprocate and rotate within the tubular member 12. This tubular member 12 is formed with a flange 27 which is arranged within a gland 28 threadedly mounted in the casing 4. On the flange 27 is arranged a cup-leather or like washer 29 and on this washer 29 is mounted a metal washer 30. The arrangement is such that leakage of oil will be prevented during the forward movement of the plunger 26. On the washer 30 is adapted to seat one end of a spring 31 which has its other end seated in a V-shaped washer 32 and abutting upon this washer 32 is a metal washer 33 which is adapted to bear against another cup-leather washer 34 mounted in the gland 28. This latter washer 34 is adapted to prevent the intake of air during the movement of the plunger 26. The gland 28 is formed with apertures 35 to permit of the passage of oil from the oil reservoir 5. This reservoir 5 is adapted to be filled with oil through the aperture in the casing 4. This aperture is closed by a screw-threaded cap 36 formed with an air vent or the like 37. The lower end of the plunger 1 is fitted with a cup-leather washer or the like 38 which is maintained in position by a nut member or the like 39 screwed on to a threaded extension of the plunger 1. Adjacent to the lower end of the plunger 1 is cut a groove 40 within which is arranged a split expansion ring 41. When the plunger 1 is in its highest position, this ring 41 expands and enters an annular groove 42 cut in the outer plunger member 2 and it will be seen that this arrangement prevents the member 1 being forced out of the plunger member 2. The lower wall of the annular groove 42 is cut away or inclined at 43 so as to contract the expansion ring 41 and permit the downward movement of the plunger 1 when the weight carried by the crutch head 44 is lowered. The crutch head 44 is preferably adjustably mounted in the plunger 1 in the well-known manner, the adjustment being effected by means of a pin 45 adapted to be positioned in one of a plurality of apertures 46 formed in a rod 47 carried by the crutch head 44, the pin 45 being arranged transversely and adapted to seat on the upper end of the plunger 1. A suitable washer 48 is arranged on the upper end of the plunger 2 to further prevent leakage between the plungers 1 and 2. The lower end of the plunger member 2 is also formed with an annular groove 49 which is cut away or inclined at 50 in a similar manner to the groove 42. Within this groove 49 is adapted to be positioned a split ring 51 when the plunger 2 is in its highest position and thus limit the outward movement of the

plunger 2. The split ring 51 is normally arranged within a groove 52 cut in the cylinder 3 and the arrangement is such that the split ring 51 will be expanded and lie in the groove 52 when the plunger 2 is lowered by the weight carried by the crutch head 44. The upper end of the cylinder 3 is maintained oil-tight by washers 53 and a threaded member 54 screwed into the said upper end of the cylinder 3. An oil leak 55 is provided for the return of any oil to the reservoir 5 which may have passed by the lower washer 53. Thus it will be seen that by arranging the packing washers in the casing 3 and in the inner telescopic member 1, the said telescopic members may be raised to a maximum height to give considerably greater lift than heretofore.

To the outer end of the pump rod 26 is pivoted at 56 a connecting rod member 57 which is rotatably mounted in a block 57^a. This block or the like 57^a, which carries an extension 57^b of the connecting rod member 57, is fitted with a pair of screws or nut members 70 which are freely mounted in apertures 58^a cut in forked arms of the lower bifurcated or forked end 58 of an operating lever 59, which is fulcrumed on a fulcrum pin 60. This fulcrum pin 60 is carried in a forked bracket 61 which is adapted to form a base for the operating lever 59. This forked bracket 61 is secured to the outer end of a member 62 which is connected at its other end to the casing 4. Thus the fulcrum portion of the jack is maintained rigidly in spaced relation to the casing portion of the jack. The lever 59 is preferably provided with an auxiliary fulcrum 63 and is so arranged that it may be adjusted in an angular position. For instance, the lever 59 may be arranged in its normally vertical position by placing a pin 64 through an aperture 65 cut in a plate 66 carried by the fulcrum 58, or it may be arranged in an inclined position by placing the pin 64 through the aperture in the lever 59, and through an aperture 67 in the plate 66, when it is inconvenient for the lever 59 to be in a normally vertical position such as when the jack has to be positioned a considerable distance under the car. The upward movement of the lever 59 is limited by a plate 68 which is secured to the forked brackets 61, and adapted to engage the forked end 58 of the operating lever 59. To the outer end of the connecting rod 57 which is rotatably mounted in the block 57^a which is carried by the forked end 58 of the lever 59 is secured a handle member 69 whereby the pump rod 26 may be rotated in the manner to be herein-after described. It will be seen that by rotatably mounting the outer end of the rod member 57 in the block 57^a the handle 69 can be rotated to rotate the pump rod 26 regardless of the angular position of the rod member 57.

In operation, and assuming that the jack is in its lowest position with the crutch head 44

positioned under, for instance, an axle of a vehicle it is desired to lift and the operating lever 59 is in a vertical position, the said lever 59 is moved downwardly to force the plunger 26 into the tubular member 12. It will be obvious that by reciprocating the plunger 26 through the medium of the operating lever 59 oil from the reservoir 5 will be forced past the valve 6 into the cylinder 3 by way of the aperture 23 in the threaded member 21 and apertures 19 in the sleeve 13. During this operation the oil will be drawn in from the reservoir 5 by way of the ports 35 and will be forced into the cylinder 3 to raise the plungers 1 and 2 and the crutch head 44. When the plungers are fully raised the split ring 41 in the plunger 1 will expand and enter the annular groove 42 cut in the outer plunger 2 and the split ring 51 normally positioned in the groove 52 of the cylinder 3 will contract and enter the groove 49 cut in the outer plunger 2. When it is desired to lower the jack the operating lever 59 is returned to its normal vertical position and the handle member 69 is turned to partially rotate the plunger 26. This partial rotation of the plunger 26 will also rotate the rod 22 and turn the threaded end 21 in the sleeve 13 and thus the forward end of the rod 22 will engage on the valve stem 18 and force the valve 6 off its seating against the action of the spring 17. The oil in the cylinder 3 will now return by way of the ports 23 and 35 and the tubular member 12 to the reservoir 5. The lowering speed of the jack can be varied according to the amount the valve 6 is moved off its seating and the lowering will be assisted by the weight carried by the crutch head 44. When the lowering operation is completed the handle 69 is turned back to its normal position so as to permit the valve 6 to function in the usual manner. The first outward or downward movement of the operating lever 59 will obviously create a vacuum in the tubular member 12 until the oil can flow from the reservoir 5 through the port 35. The forward movement of the plunger will force the oil past the valve 6 into the cylinder 3 and the sequence of operations will be repeated when it is required to again use the jack. The wheels 7 on the forward end of the jack will assist the positioning of the jack under the car and it will be seen that the jack will be adequately supported when one or both of the brackets 10 are in their outward position.

In a modified construction as shown in Figures 9 to 13, and when the invention is applied to a jack suitable for ordinary use and for carrying on a car, the casing 4 is formed with a bifurcated bracket 71 which is adapted to carry a fulcrum pin 72 on which is mounted a handle socket 73. This operating handle socket 73 is formed with a pair of downwardly extending arms 74 on which are

mounted one end of connecting links 75. The other ends of the connecting links 75 are connected to a sleeve 76 which is mounted on the outer end of the plunger rod 26 which is adapted to reciprocate within the casing 4 and operate in a similar manner to that previously described. The casing portion 4 of the jack and the plunger members 1 and 2 will not be further described as the construction and operation is similar to the previous construction. Within the socket 73 is adapted to be placed the lower end of an operating handle 77 of any suitable length. The lower end operating handle or lever 77 is formed or provided with a bayonet joint or fitting 78 which is adapted to co-operate with a bayonet fitting 79 formed or provided in the interior of the socket 73. The arrangement is such that when the handle 77 is forced into the socket 73 and given a partial rotation, the said handle 77 will be detachably locked in position in the co-operating bayonet fittings by the action of a spring 80 disposed within a recess formed in the lower end of the said socket 73. The extreme lower end of the handle or lever 77 is formed with another bayonet socket fitting 81 which is adapted to co-operate with a socket pin fitting 82 secured on the outer end of the plunger rod 26.

In operation, and when it is desired to raise this modified form of jack, the casing 4 is positioned under the vehicle and the crutch head 44 is arranged under the portion of the vehicle to be lifted. The operating handle lever 77 is pushed into the handle socket 73 against the action of the spring 80 and partially rotated so that the bayonet fittings 78 and 79 co-operate to hold the handle 77 in position. Upon the downward and upward movement of the handle 77 the plunger 26 will be reciprocated through the medium of the links 75 and arms 74 and thus the oil will be forced from the reservoir 5 past the valve 6 into the cylinder 3 to raise the plunger members 1 and 2 in a manner similar to that described in the previous construction. A suitable stop 83 is provided on the bracket 71 to co-operate with a squared end 84 formed on the socket 73 and thus limit the upward movement of the handle or lever 77. When it is desired to lower the jack the handle lever 77 is forced inwardly against the action of the spring 80 and partially rotated to unlock the co-operating fittings 78 and 79 and permit of the withdrawal of the said handle. The extreme lower end of the handle or lever 77 is now inserted in the socket pin fitting 82 on the plunger rod 26 and partially rotated to rotate the plunger rod 26. This rotation of the plunger rod 26 will act in a similar manner to that previously described in connection with the first construction and move the valve 6 off its seating and thus the weight carried by the crutch head 44 will be lowered.

automatically. In this modified construction, the wheels 7 and supporting brackets 10 are omitted, but it will be understood that they may be provided if desired.

5 It will be seen that by the invention there is provided a hydraulic jack for garage or ordinary use which will have a higher lift than is obtained by hydraulic jacks at present constructed and further the lift may be 10 increased by providing more than two telescopic members.

Reference is made to applicant's co-pending application filed September 8, 1926, Serial No. 134,227, for claims directed to subject- 15 matter specifically described but not claimed herein.

What I claim is:—

1. A lifting jack of the hydraulic type including a load lifter, a pump rod, hydraulic 20 means to exert a raising force on the load lifter by reciprocating the pump rod, and means to relieve the load lifter of such force by rotative operation of the pump rod.

2. A lifting jack of the hydraulic type including a load lifter, fluid pressure means whereby the load lifter may be raised or lowered, and a single valve intermediate the fluid pressure means and load lifter, said valve being freely responsive to fluid pressure to admit the fluid under pressure to the load lifter and adapted for operation by the fluid pressure means to relieve the load lifter of the fluid pressure.

3. A lifting jack of the hydraulic type including a load lifter, a motive fluid reservoir, a pump rod for directing a motive fluid from said reservoir to raise the load lifter, a lever for reciprocating said rod to raise the load lifter, and means responsive to a rotation of 40 said pump rod to relieve the load lifter of the sustaining pressure of said motive fluid.

4. In a hydraulic jack, a load support, a pump rod for directing a motive fluid from a suitable source to and beneath said support 45 for raising the same, a valve opening under the pressure of the motive fluid responsive to pump rod movement to permit the passage of the motive fluid to the load support, a valve rod adapted in rotation in one direction to 50 engage and open the valve, said pump rod being mounted for rotation to similarly operate the valve rod whereby rotation of the pump rod will rotate the valve rod to open the valve for relieving the pressure beneath 55 the load support.

5. In a hydraulic lifting jack, a lifting plunger, means for pumping a fluid to and beneath the plunger to raise the same, said means including a reciprocating pump rod 60 and a valve opening under the pressure of the fluid incident to the operation of the pump rod, a valve rod connected to the valve, and adapted in movement to open the valve, and means whereby the pump rod may be independently actuated to operate the valve 65

rod to thereby relieve the fluid pressure beneath the plunger.

6. A hydraulic lifting jack, a lifting plunger, means for pumping a motive fluid beneath said plunger, said means including a reciprocating pump rod and a valve past which the fluid is pumped, a valve rod adapted in rotative movement to open the valve, the valve rod and pump rod being connected for relative sliding movement without permitting a 70 relative rotary movement, and means whereby the pump rod may be rotated at will to operate the valve rod.

7. A hydraulic lifting jack including a plunger to be operated by the pressure of a 80 motive fluid, a pump for directing the motive fluid under pressure beneath the plunger, said pump including a pump rod adapted for reciprocating movement and a valve to normally prevent return of such fluid from beneath the plunger, a valve rod for operating the valve independent of the fluid pressure, said valve rod being non-circular in cross section and slidably fitting a correspondingly shaped bore in the pump rod, and means 85 whereby the pump rod may be rotated to correspondingly actuate the valve rod.

8. A lifting jack of hydraulic type comprising a casing having a reservoir, a cylinder, a tubular member intermediate the reservoir and cylinder, a pair of telescopic members slidably mounted in the cylinder, a valve positioned adjacent to the lower end of the cylinder to close the end of the tubular member, a pump rod adapted to reciprocate in the 100 tubular member, an operating lever connected to said pump rod, a sleeve arranged in the tubular member and carrying said valve, an angular shaped rod formed with a thread to cooperate with a thread formed in said sleeve, 105 the pump rod being formed with a bore corresponding in size and shape to the sectional dimensions of the angular rod to insure rotative movement of the angular rod in the rotative movement of the pump rod, and 110 spring means for maintaining the valve on its seat.

9. A lifting jack as claimed in claim 8, wherein the pump rod sleeve is threaded in the casing and provided with washers and a 115 spring to space the said washers which are adapted to prevent leakage of oil during the reciprocation of the piston rod, said sleeve being formed with apertures communicating with the reservoir and the tubular member. 120

10. A lifting jack as claimed in claim 8, wherein the operating lever is formed with a forked end in which a connecting rod is mounted for rotary motion, said connecting rod having a handle at one end and being connected at its other end to the reciprocating plunger, means being provided to limit the movement of the operating lever. 125

11. A lifting jack as claimed in claim 8, wherein the operating lever is formed with an 130

auxiliary fulcrum and means are provided for the angular adjustment of the said operating lever about the said fulcrum.

12. A lifting jack as claimed in claim 8,
5 wherein the casing is fitted with a pivoted sleeve member formed with depending arms connected by links to the reciprocating plunger rod, said sleeve having means to detach-

ably lock a lever or operating handle therein, said plunger rod being also fitted with means 10 for detachably locking the lever or operating handle therein.

In testimony whereof I have hereunto signed my name.

WILLIAM BEARD LAKE.
